CONCEALED MANIFOLD FOR GAS STOVES

Joseph E. Leonard, Berkeley, Calif., assignor to
 Hammer-Bray Company, Oakland, Calif., a
 corporation of California

Application April 16, 1930, Serial No. 444,691

7 Claims. (Cl. 126—39)

This invention relates to improvements in gas stoves and ranges and more particularly to a novel and efficient shield structure for concealing and protecting the gas manifold, valves and associated stove parts.

In order to improve the appearance and promote the cleanliness and sanitation of gas stoves and ranges, the present practice has led to use of shields, aprons or extensions arranged to 10 conceal the manifold and valves. A common difficulty with such arrangements is that the stove heat is objectionably confined by the shields, aprons or extensions, and also too readily transmitted to the shields and manifolds and 15 valves owing to the construction of the shields and manner of connection of the shields and manifolds with the stove. Thus the manifolds, valves and shields become overheated, particularly in closed top stoves, with the result that 20 not only is the operator likely to burn the hands in manipulating the valves, but the valves tend to stick, or leak and are often damaged.

Accordingly an object of my invention is to provide a manifold concealing and protecting arrangement which will eliminate the objections and difficulties hereinbefore noted, in a particularly efficient manner.

Another object of my invention is to provide a shield means of the character described in 30 which air is permitted to circulate freely beneath and behind the shield and around the manifold and valves in such manner as to prevent overheating of the manifold and valves and maintain the outer or exposed portions of the shield 35 and valves comparatively cool.

Still another object of my invention is to provide a manifold concealing and shielding arrangement of the character described in which the manifold and shield are free from connection and contact with the stove top and such parts of the stove which, if connected to or engaged with, would cause the shield, manifold and associated parts to become overheated.

A further object is to provide a shield arrangement of the character described which will cause 45 the heated air and air circulating beneath and behind the shield to pass upward into the burner chamber of the stove top and out through the vent or flue of the stove rather than confine the 50 heat to the space beneath the shield.

This invention further resides in the provision of a new and efficient form of shield which has a plurality of air circulating passages in an arrangement which causes a more effective air circulation around the manifold and burners and

maintains the outer surface of the shield in a cool condition.

Another feature of the invention is the provision of a sectional shield of novel arrangement and construction greatly facilitating an assembling and disassembling thereof relative to the stove and an easy adjustment of the valves.

Further, a feature of importance is a new manifold arrangement wherein the manifold is disposed below the valves and in such relation to 10 the stove top and shield as to be more effectively spaced and insulated from heat of the stove than is possible with the usual manifold disposition in gas stoves.

Yet another object is to provide a shield means 15 of the character described which is of simple and inexpensive construction, capable of being readily and easily set up and taken down on various kinds and makes of stoves, and which disposes the valve handles in a most convenient 20 position while at the same time greatly improving the appearance of the stove.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of 30 the invention as set forth in the claims.

Referring to the drawing:

Figure 1 is a front elevation of a gas stove equipped with the shield of my invention. 35

Figure 2 is an enlarged vertical sectional view through the shield and parts of the stove.

Figure 3 is a longitudinal sectional view taken on the plane of line 3—3 of Figure 2.

The present embodiment of my invention as 40 shown in detail in the accompanying drawing forms a part of a gas stove of the closed cooking top type but it may also be effectively used in connection with open top stoves.

As here shown the stove includes a closed 45 cooking top 1 between which are vertical side or wall members 2 defining with the top a burner chamber 3 for burners, a gas inlet pipe portion 4 of a burner being here indicated. The chamber 2 is open at the point where the burners extend outward for operative connection with the gas manifold whereas at the back said chamber is vented to a flue in the usual manner, not shown.

The concealed manifold arrangement of my in- 55

vention comprises a shield structure in the general form of an elongated rectangular casing 5 detachably secured at its ends to the vertical walls 2 and disposed in front of the stove beneath the top 1 to conceal the manifold and valves. Upper and lower sides of the shield are open and the upper open side is disposed in spaced relation below and inwardly of a forward overhanging member 6 of the top, in position 10 to direct air currents into the chamber through a passage 7 provided beneath the top. The manifold 8 is carried by the shield and the valves 9 are supported on top of the manifold and connected to the burners in the usual manner. The 15 valve stems 10 project outward through orifices 11 in the shield and have handles 12 thereon operable on the outer side of the shield. With this arrangement it is seen that the shield is free from connection with and spaced from the cooking 20 top 1. The manifold 8 is likewise free from connection with said top and spaced well below the top and outward from the front of the stove as well as spaced from opposed sides of the shield. Therefore, air will enter the lower open side of 25 the shield and also through the space 13 between the top and shield and will pass upward and inward and around the manifold and valves through the upper open end of the shield and passage 7 into the burner chamber from whence 30 it vents in the usual manner through the flue, not shown. With a free circulation of air thus provided for and the shield and burner disconnected and spaced from the cooking top, overheating of the manifold, valves and shield is 35 effectively prevented and the outer side of the shield is maintained in a comparatively cool condition.

To facilitate the assembling and disassembling of the shield and easy access to the valves, the 40 shield is of sectional construction, the upper front portion 14 being separable from the fixed section 15. The portion 14 is arranged to provide a rearwardly and upwardly sloping front for the shield and has the orifices or slots 11 cut through to the lower edge thereof whereby it may be readily fitted over or removed from the valve stems. The end and lower edges of the removable section 14 are provided with inwardly 45 offset flanges 16 arranged to rest upon lugs 17 on the inner sides of the front and end walls 18 and 19 respectively of the fixed section 15.

To provide for attachment of the shield to the stove, the end walls 19 have inturned flanges 20 on their inner vertical edges, which flanges are 50 secured by bolts 21 to angle iron members 22 fixed to the vertical side walls 2 of the stove. The rear wall 23 of the fixed section 15 of the shield is upwardly and rearwardly inclined from its lower end to a point beneath the burners and then extends vertically above the plane of the end walls 19 and terminates in a baffle portion 24 spaced below the cooking top 1 and having an inturned horizontal flange 25 on its upper end. 55 This portion 24 with the portion 26 of the stove top defines the passage 7 which communicates the space at the top of the shield with the interior of the burner space or compartment of the stove and also baffles the heat from within the burner 60 compartment. In this rear wall 23 are openings 27 through which the gas inlet pipes 4 of the burners extend.

To protect the manifold from the heat of the stove a baffle plate 28 is provided on the rear wall 75 23 and extends forward therefrom beneath the

adjacent ends of the burners. In order to support the manifold on the shield without connection of the manifold with the top 1, the lower section 15 is provided on its front wall 18 with inwardly extending arms 29 on which the manifold 5 is secured by clamps 30.

To insure an effective circulation of cooling air around the manifold and valves, a partition wall 31 is secured to the lower part of the shield in spaced substantially parallel relation to the lower part of the rear wall 23. By this arrangement a wide passage 32 is formed in the lower part of the shield between the front and partition walls, and a smaller passage 33 is defined between the partition and rear wall. The manifold lies within the upper part of the passage 32 in such position that air flowing upward through said passage is directed against and around both sides of the manifold and of course around the valves supported thereon. The baffle plate 28 is 20 at the upper end of the passage 33 and acts to direct the air currents from said passage laterally outward against and past the manifold and valves. Thus the two air streams directed by the passages 32 and 33 to and around the manifold 25 and valves prevent overheating of said parts and maintain them in a comparatively cool state. Furthermore, these two air passages and the walls 23 and 31 thereof provide for an effective insulation of the outer or front wall 18 and the 30 removable section 14, also the valve handles, and thereby maintain the front of the shield and the valve handles in a cool state to prevent burning of the hands or discomfort of a person touching the front of the shield or said handles. 35

It will now be clear that the concealed manifold arrangement of my invention will provide the advantages hereinbefore set forth in a particularly efficient manner and primarily by reason of the facts that, first the shield effectively 40 conceals the manifold, valves, etc., and improves the appearance of the stove; second, the shield is free from connection with and spaced from the stove top whereby to avoid a direct conduct of heat to the manifold, valves, etc.; third, 45 the shield provides for a free air circulation about the manifold, valves and shield parts and prevents overheating of the manifold, valves and said parts, etc., as well as maintains the outer or exposed portions of the shield and valves 50 in a cool state; fourth, the air circulated beneath the shield is conducted into the burner chamber and passes out through the flue and therefore no heated air or heat trap is provided beneath and behind or by the shield; fifth, the manifold is 55 free from connection with the stove top to avoid conduct of heat thereto and is supported by the shield in such manner as to effectively insulate it from the heat of the stove and thereby prevent overheating thereof and its attendant bad effects 60 hereinbefore enumerated; and lastly, the sectional construction of the shield facilitates the assembling and disassembling thereof and provides for easy access to the valves for adjustment thereof. 65

It is to be noted that when the manifold arrangement of this invention is associated with an open top stove, the space 13 between the top of the shield and the stove top may serve as a vent to the atmosphere. However, with a closed top 70 stove wherein a strong draft is created through the passage 7, the tendency is for an intaking action through the passage 13 rather than a venting of the air currents through said passage.

I claim:

1. In a gas stove, a stove top, a burner compartment beneath said top, burners in said compartment, a gas manifold, valves carried by said manifold and connected with said burners, a shield enclosing and concealing said manifold and valves, and a partition wall in the shield defining with other walls of the shield a plurality of air passages arranged to direct currents of air to and past said manifold and valves.
2. In a gas stove, a stove top, a burner chamber beneath said top, burners in said chamber, a gas manifold, valves associated with said manifold and burners, a shield enclosing said manifold and valves and comprising a sectional front wall, one section of which is removable, a rear wall and end walls joining the front and rear walls, the upper side of said rear wall opening at a point above the manifold and valves, and the lower side of said shield being open to the atmosphere at a point below said manifold and valves.
3. In a gas stove, a stove top, a burner chamber beneath said top, burners in said chamber, a gas manifold, valves associated with said manifold and burners, a shield enclosing said manifold and valves and comprising a front wall lying in front of said manifold and valves, a rear wall lying in the rear of said manifold and valves and end walls joining the front and rear walls, the upper side of said rear wall opening into said chamber at a point above the burners but beneath and spaced from said top, and the lower side of said shield being open to the atmosphere at a point below said manifold and valves.
4. In a gas stove, a stove top, a burner compartment beneath said top, burners in said compartment, a gas manifold, valves associated with said manifold and burners, and a shield comprising a front wall concealing said manifold and valves and a rear wall disposed in the rear of said manifold and valves, said front and rear walls providing therebetween an air passage around and past said manifold and valves, said passage opening into the burner chamber at a point above the burner and beneath said top and opening to the atmosphere at a point below the manifold and valves.
5. In a gas stove, a stove top, a burner compartment beneath said top, a burner in said compartment, a gas pipe leading to said burner, a gas manifold, a valve connecting said manifold and pipe, a shield arranged to lie in front of and conceal the manifold and valve, and a rear wall disposed between the manifold, valve and said compartment and extending below said pipe, said shield and rear wall providing therebetween an air passage, said rear wall having a perforation therein below said pipe connecting said passage with said compartment and being spaced at the upper end thereof from said top to provide an opening communicating said passage with said compartment.
6. In a gas stove, a stove top, a burner compartment beneath said top, a burner in said compartment, a gas pipe leading to said burner, a gas manifold, a valve connecting said manifold and pipe, a shield arranged to lie in front of and conceal the manifold and valve, a rear wall disposed between the manifold, valve and said compartment and extending below said pipe, said shield and rear wall providing therebetween an air passage, said rear wall having a perforation therein below said pipe connecting said passage with said compartment, and a deflector plate arranged to deflect air in said passage away from said perforation and direct said air to said manifold and valve.
7. In a gas stove, a stove top, a burner compartment beneath said top, a burner in said compartment, a gas manifold, a valve associated with said manifold and burner, a shield lying in front of and concealing said manifold and valve, a rear wall lying between said manifold, valve and said compartment and defining with said shield an air passage, and a deflector plate in said passage for directing the flow of air therethrough around and past said manifold and valve.

JOSEPH E. LEONARD.
